UNITED STATES PATENT OFFICE.

WILHELM SCHEERER, OF TUTTLINGEN, GERMANY.

SPECULUM.

SPECIFICATION forming part of Letters Patent No. 516,842, dated March 20, 1894.

Application filed December 8, 1893. Serial No. 493,168. (No model.)

To all whom it may concern:

Be it known that I, WILHELM SCHEERER, residing at Tuttlingen, Würtemberg, Germany, have invented a new and useful Improvement 5 in Surgical Instruments, of which the following is a specification.

The present invention relates to a conical spring adjustment for specula and similar instruments.

10 The object of my invention is to produce a portable speculum.

The invention consists of such features, details of construction, and combinations of parts as will first be described in connection 15 with the accompanying drawings, and then particularly pointed out in the claims.

In the drawings—Figure 1 is a front elevation of a speculum embodying my invention. Fig. 2 is a side elevation of the same. Fig. 3 20 is a rear elevation. Fig. 4 is a detail side elevation. Fig. 5 is a detail plan view. Fig. 6 is a front elevation of the speculum proper. Fig. 7 is a plan view of the same.

An inspection of the accompanying drawings representing a speculum with the handle, shows that the mode of adjustment of the same, under my invention, differs from those heretofore made in being essentially simplified by dispensing with all screws, eccentric 25 clamps, and the like. The handle, A, is provided at its upper end with a smooth conically-enlarged or flaring shank, a, while the speculum proper, B, is provided with a correspondingly-conical spring sleeve, provided with the 30 open slot, c, and the flaps or lips, d, d, which have a spring action. In order to prevent the twisting of the speculum proper, when in use, the end of the shank, a, may be provided with a lug, or short stud, f, either fixed, or 35 adapted to be unscrewed from the shank.

When it is desired to connect the speculum proper with the handle, A, for use, the former is placed into the position indicated in dotted lines, in Fig. 4, the part of the handle, designated by e, entering the slot, c, in the 45 sleeve of the speculum proper. The part, e, is, for this purpose, flattened to the width of the slot, c. After the part, e, has been inserted into the slot, c, the reduced part of the conical shank, a, is drawn down into the 50 sleeve until the stud, f, nearly touches the speculum proper, B, when the latter is swung around one hundred and eighty degrees, the shank being then drawn down tightly into the sleeve, the stud, f, engaging with the 55 slot, c.

What I claim, and desire to secure by Letters Patent, is—

1. In a two-part speculum, the combination, of a handle provided with a conical shank, 60 with a speculum proper having an open spring sleeve, adapted to engage the shank, substantially as set forth.

2. In a two-part speculum, the combination, with a handle provided with a conical shank, 65 and a speculum proper having an open spring sleeve arranged to engage the shank, of a stud on the conical shank adapted to engage the open slot in the sleeve, to prevent twisting or turning of the speculum proper, substantially as set forth.

In testimony whereof I have signed this specification in the presence of two subscribing witnesses.

WILHELM SCHEERER.

Witnesses:

AUGUST B. DRANTZ,
ARTHUR HOFMANN.
